UNITED STATES PATENT OFFICE.

JULIUS LUNDBLAD, OF JELLY, CALIFORNIA.

FRUIT-PICKER'S GLOVE.

Application filed September 27, 1926. Serial No. 138,007.

This invention relates to new and useful improvements in gloves and has for its primary object to provide a glove that is especially constructed for use in the picking of small fruit such as berries, plums, cherries, and also olives and the like, the glove being equipped at the side of the palm portion with a receptacle so as to set the articles after the same have been picked by the fingers of the person wearing the glove.

A further object of the invention is to provide a glove that is equipped with a receptacle of such a nature and so associated with the glove body as not to interfere with the picking operation.

Other objects will become apparent as the nature of the invention is better understood, the same comprising the novel form of glove hereinafter more fully described, shown in the accompanying drawing and claimed.

In the drawing wherein like reference characters indicate corresponding parts in both of the views:

Figure 1 is a full size perspective of glove constructed in accordance with the present invention, the same being disclosed as actually associated with the hand of the wearer, and

Figure 2 is a side perspective of the glove, per se.

Now having particular reference to the drawing wherein there is disclosed but one embodiment of the present invention, 5 designates a glove proper consisting of a main body constructed generally similar to workmen's gloves and having finger and thumb receiving units 6 and 7, respectively. The fore and index finger receiving unit as well as the thumb receiving unit are of 10 relatively short dimensions and are open at their ends in order to permit said fore and index finger as well as the thumb of the berry picker to project therethrough as clearly indicated in Figure 1 in order that 15 these fingers may be properly employed in the picking operation.

Suitably secured to the palm portion of the glove body at the edge thereof remote from the thumb unit 7 is a depending pouch 50 of the same material as the glove. The small finger receiving unit 9 is constructed for entirely enclosing the little finger of the

berry picker and the material forming said little finger receiving unit is stitched to the upper edge of the pouch 8 so as to assist in maintaining the pouch in vertical position during the picking operation. The opposite upper edge of the pouch is also secured to the palm portion of the glove body alongside of the thumb receiving unit 7 by a web 10 that is preferably integral with the material forming said pouch as also disclosed in Figure 1.

The pouch 8 and the glove body attaching end of the web 10 are preferably secured to the glove body by stitching as indicated by the reference characters 11 and 12 in Figure 2.

There is preferably, although not absolutely necessarily arranged within the pouch 8 a metallic receptacle 13 that provides a rigid lining for the interior of the pouch and for preventing the material forming the pouch from becoming soiled by the contact of the berries therewith.

It will be obvious that as the fruit is picked by the exposed fingers of the berry picker the same may be immediately dropped from the fingers and the same will be effectively caught within the pouch 8. As soon as the pouch has become filled, the fruit or other material therein may be conveniently dumped into a larger receptacle carried by the picker or disposed upon the ground.

In view of the foregoing description which when considered in conjunction with the accompanying drawing it will at once be apparent that I have provided a highly novel, simple, and efficient form of glove that is well adapted for all the purposes heretofore designated and even though I have herein shown and described but a single embodiment of the invention, and this embodiment consisting of certain detail structural elements it is nevertheless to be understood that other embodiments may be had and that departures may be made from the structure disclosed in the drawing without affecting the spirit and scope of the appended claim.

Having thus described the invention, what I claim is:

In a hand appliance for use by fruit

pickers, a glove including a wrist band, a body portion connected with said band, and individual finger stalls connected to the body portion, the stall for the little finger being complete and enclosed at its outer end, the stalls for the remaining fingers and thumb being open to allow the latter to pass through and beyond the open end, an open

top collection and receiving pouch having a portion of the top edge connected with the little finger stall and palm portion of said body, and a connecting and supporting web connected with the upper end of the pouch and with the palm and thumb stall. 10

In testimony whereof I affix my signature.
JULIUS LUNDBLAD.
